UNITED STATES PATENT OFFICE.

CHARLES GÉGAUFF, OF MULHOUSE, HAUT-RHIN, FRANCE, ASSIGNOR TO SOCIÉTÉ ALSACIENNE DE CONSTRUCTIONS MÉCANIQUES, OF MULHOUSE, HAUT-RHIN, FRANCE.

MEANS FOR CONTROLLING THE NIPPERS IN HEILMANN AND LIKE COMBERS.

Application filed July 18, 1928, Serial No. 293,535, and in Great Britain August 2, 1927.

My invention relates to the type of comb
er known as the rectilinear type in which the
nippers holding the lap to be combed have
an alternating translatory movement be-
5 tween the circular comb and the detaching
rollers, which are fixed in space, and in which
the path of the end of the upper jaw of the
nippers is, during combing, tangential to the
periphery of the circular comb and remains
10 invariable while the lower jaw assumes a
variable position which is regulated by the
pressure of a spring imparting pressure to
the closed nippers and which depends in con-
sequence on the variable thickness of the
15 lap where it is gripped by the nippers.

In combers of this type it is absolutely
necessary to avoid completely vibrations of
the end of the upper jaw of the nippers dur-
ing combing so as to be able to regulate to a
20 very small degree the distance between the
end of the nippers and needle points of the
circular comb in order to obtain proper comb-
ing because this distance influences to a very
great extent the character of the combed ma-
25 terial.

Existing combers may be divided under
this heading into two classes, viz:—

Class 1. Those in which the end of the upper
jaw has a constant invariable path, i. e.
30 a path which is not dependent on accidental
variations of the thickness of the lap combed.
This class of machine is the most modern and
most perfect and it is this class to which the
comber of the present invention belongs.

35 Class 2. Those in which the accidental
thickness of the lap influences the distance
of the end of the upper jaw from the needles
on the circular comb, i. e. those in which the
distance is variable and increases consider-
40 ably with the thickness of the lap. In practice,
however, such accidental variations in
thickness are constantly being produced in
consequence of the irregularity in the thick-
ness of the lap as also during the times when
45 a new lap is being attached, the old one be-
ing exhausted.

50 It is clear that in the second class the most
desirable minimum distance between the nippers
and the needles cannot be obtained ex-
cept at times when the lap is thinnest while
at all other times when the lap is thicker this
distance is increased by the excess thickness
of the lap so that the character of the combed
material will be less satisfactory.

My invention relates more particularly to 55
improvements in the guiding mechanism of
the lower jaw. The accompanying draw-
ings illustrate diagrammatically different ar-
rangements adopted for said guiding mecha-
nism.

60 Referring to the drawings:—
Fig. 1 illustrates one form of construction
showing the nippers in the combing position,
Fig. 2 shows the same construction, the
nippers being close to the detaching rollers, 65
Fig. 3 is a detail,

Fig. 4 is a second form of construction,
with the nippers in the combing position.

It has already been proposed to guide the
upper jaw of the nippers in such manner 70
that the end *e* of this jaw (see Fig. 1), during
combing by the circular comb, is pressed di-
rectly and without the interposition of any
connecting members or intermediate levers
against an absolutely fixed point *l'* on the 75
framework of the machine, i. e. against a
roller *l*, the spindle *l'* of which is fixed to the
framework itself.

This prevents any kind of vibration arising
from the elasticity of interposed levers or 80
from the play in connecting members inter-
posed between the absolutely fixed point (the
spindle *l'*) and the end *e* of the nippers. As
soon as the combing operation is completed
the nippers advance towards the detaching 85
rollers *b*, *b'* and open progressively in their
passage due to the form of the cam *m*, the
upper jaw of the nippers being at the same
time continuously pressed against the roller
l (due to the action of a spring *n*). 90

The nippers having reached the detaching
position in relation to the detaching rollers
b, *b'* (see Fig. 2) no longer possess the same
great rigidity against vibrations and move-
ments which they possessed during the comb-
ing operation (Fig. 1 position) because the
movement of the connecting members such
as *h* and *i* as also the vibrations of the two
arms *u*, and *h*, permit the ends *e* and *f* of the
nippers to vibrate but this is at the moment 100
of detachment where precision and absolute
immovability are no longer indispensable to
the satisfactory operation of the combing since
the nippers are then opened and inoperative.

Nevertheless experience has shown that it 105
was necessary in order to be able to obtain
a high speed of movement of the machine to
improve also the mechanism guiding the

lower jaw i. e., causing the end f of the lower jaw to travel in the path q, q' (shown in dotted lines in Fig. 1) which is necessary for operation. The means hitherto employed for this purpose are imperfect and act discontinuously and suddenly at the moment the jaws are closed, that is to say, at the moment when the two ends f and e of the jaws meet in order to nip the lap shocks and consequent vibrations of the nippers are always produced which prevent the machine from working at high speeds.

The present invention has for its object improvements in the guiding mechanism of the lower jaw of the nippers so as to avoid these shocks of the closing of the nippers and in consequence also the vibrations which accompany them, permitting the machine to run more quickly.

These improvements are essentially characterized by this that the guiding mechanism of the lower jaw is constituted by a roller constantly pressed against a part, suitably profiled in the form of a cam, on the arm carrying the lower jaw of the nippers. This roller is able to yield very slightly by the effect of pressure from the cam, that is to say, is capable of being displaced slightly, which displacement may be as small as desired, i. e., practically nil; this very small displacement transmitting to the roller all the pressure of a permanently stretched spring and producing thus the pressure on the nippers without appreciable shock.

Each arm carrying the lower jaw f of the nippers is profiled on its lower side, between u and u' in the form of a curved line (cam) pressing continuously against the roller x , the spindle x' of which is fixed to a member which may yield very slightly under the effect of a certain pressure from the cam u, u' .

In the translatory movement of the nippers from combing to detaching position and vice-versa, the roller x rolls over the cam u, u' which is displaced, and the end of the lower jaw describes an approximately invariable trajectory q, q' necessary for the operation.

The roller may thus have a very small displacement (which may be as small as desired, e. g. practically nil) at the moment the jaws are closed. This closure of the jaws results from the relative movement of the two ends f and e of the jaws, a movement produced by the form of the two cams m, m' with the roller l and u, u' with the roller x by virtue of which the ends f and e approach one another during the displacement of the nippers towards the comb; at the moment when the two ends meet, their relative speed has become very low, practically nil, and the nipping pressure on the lap is produced without shock by the very small displacement of the roller x then occurring.

The slight displacement of the roller x

may produce the nipping pressure of the nippers on the lap as follows:—The roller x is carried by a blade spring y (see Figs. 1, 2 and 3) or by a helical spring (see Fig. 4). This spring is not unconstrained but is in a state of permanent tension i. e., in a condition of permanent elastic deformation maintained by a stress preventing it from assuming its free form. This stress is produced in the construction shown in Figs. 1, 2 and 3 by the fixed arm z , (fixed to the frame t of the machine), the regulating screw v of which serves as a fixed abutment for the stretched spring y and bears in consequence the whole pressure due to the deformation of the spring; this deformation is indicated in Fig. 3 which shows in dotted lines at x_1 the position which the roller x would naturally assume if the spring y were released, i. e. if the screw v and its arm z were removed.

It will be seen that it is sufficient that the roller x should be pressed back by the cam u, u' through an amount as small as desired, (for example a fraction of a millimeter) in order that the pressure of the spring which is exerted against the fixed screw v is exerted now entirely on the cam u, u' and consequently against the ends of the nippers and may produce nipping of the lap. The shock produced will be practically nil having regard to the smallness of the movement communicated to the roller x .

As a variant of the construction, the arrangement employing the blade spring y shown in Figs. 1, 2 and 3 may be replaced by another having a coil spring p (see Fig. 4). The roller x is in this instance carried by a small arm s loose on a fixed spindle j carried by the frame t and this arm receives directly the pressure of the compressed spring p (preliminarily compressed by the screw r' on the fixed arm r) and transmits this pressure to the screw v which is fixed in space. A very small movement of the roller x (as small as desired) will be sufficient to transfer the whole pressure of the spring to the cam u, u' , which has produced the small movement of the roller and this displacement of the point of application of the pressure will be effected without shock because of the smallness of the movement of the roller.

It has already been suggested to guide the lower jaw by a roller moving over a guide cam but in such a known arrangement the roller and the cam were rigidly fixed on their respective supports and could not in consequence prevent shocks at the moment of closure of the nippers.

What I claim is:

1. In a combing of the Heilmann or like type comprising a pair of detaching rollers with an interposed leather belt, a circular comb and nippers holding the lap to be combed, which nippers are displaced tangentially relative to the circular comb and

receive an alternating translatory movement extending from said circular comb to the detaching rollers, in order to cause the lower jaw of said nippers to describe a desired trajectory, a mechanism comprising in combination: a first arm carrying the lower jaw of the nippers and receiving an alternating translatory movement, a cam like rolling path provided on said arm, a yielding tensioned member provided to the framework of the comber, means adapted on said frame for adjusting the tension of the said member and the normal position in space thereof, a roller carried by said member and pressed against said rolling path, a second arm hinged to the first arm and carrying the upper jaw of the nippers, a rolling path profiled in form of a cam on said second arm, a roller provided to the framework of the comber and rolling against the path of the said second arm and resilient means acting as to open the said nippers, said combination being able to exert suitable elastic pressure on the jaws of the nippers without appreciable shock or vibration.

2. In a comber of the Heilmann or like type, comprising a pair of detaching rollers with an interposed leather belt, a circular comb and nippers holding the lap to be combed, which nippers are displaced tangentially relative to the circular comb and receive an alternating translatory movement extending from said circular comb to said detaching rollers, a mechanism comprising in combination, a first arm carrying the lower jaw of the nippers and receiving an alternating translatory movement, a cam like rolling path provided on said arm, an elastically blade fixed to the framework of the comber and capable of being permanently stretched, a roller mounted on the yielding end of said blade, a rigid member fixed to the said framework and carrying means for adjusting the tension of said blade, a second arm carrying the upper

jaw of the nippers and hinged to the first arm carrying the lower jaw, a rolling path profiled in form of a cam on the second arm, a roller mounted on the framework of the comber and rolling against the last rolling path and resilient means acting as to open the nippers, said combination being able to exert the suitable elastic pressure on the nippers without appreciable shock or vibration.

3. In a comber of the Heilmann or like type, comprising a pair of detaching rollers with an interposed leather belt, a circular comb and nippers holding the lap to be combed which nippers are displaced tangentially relative to the circular comb and receive an alternating translatory movement extending from said circular comb to the detaching rollers, a mechanism comprising in combination: a first arm carrying the lower jaw of the nippers and receiving an alternating translatory movement, a cam like rolling path provided on said arm, a roller fixed to the end of a small arm pivotally mounted at a fixed point of the framework of the comber, a spring acting against said end of the small arm, a first adjustable abutment adapted to the frame of the comber for limiting the movement of said end of the small arm, a second adjustable abutment provided on said framework for adjusting the tension of said spring, a second arm hinged to the first and carrying the upper jaw of the nippers, a rolling path profiled in form of a cam and provided on the said second arm, a roller mounted on the frame of the comber and rolling against the last mentioned rolling path and resilient means acting as to open the said nippers, said combination being able to exert a suitable elastic pressure on the jaws of the nippers without appreciable shock or vibration.

In witness whereof I affix my signature.

CHARLES GÉGAUFF.
